(57) **CLAIM**

The ornamental design for an explosive detection kit, as shown and described.

DESCRIPTION

FIG. 1 is a front elevational view of an explosive detection kit showing the new design;
FIG. 2 is a rear elevational view thereof;
FIG. 3 is a right side view thereof;
FIG. 4 is a top left and rear perspective view thereof;
FIG. 5 is a top plan view thereof;
FIG. 6 is a bottom plan view thereof; and,
FIG. 7 is a top right and front perspective view thereof.
The broken line illustration of environmental and other structures in the drawings are not part of the design sought to be patented.
